UNITED STATES PATENT OFFICE.

REGINALD V. WILLIAMS, OF BUFFALO, NEW YORK.

DENTAL CLASP.

Application filed September 2, 1922. Serial No. 585,981.

To all whom it may concern:

Be it known that I, REGINALD V. WILLIAMS, a citizen of the United States, residing at Buffalo, in the county of Erie and 5 State of New York, have invented new and useful Improvements in Dental Clasps, of which the following is a specification.

This invention relates to the clasps employed for removably securing dental plates 10 or saddles to natural teeth.

One of the objects of the invention is to provide an improved jointed clasp of this character, which, while capable of firmly grasping a tooth, permits a free vertical 15 movement of the denture or saddle to a limited extent, so as to relieve the clasp and the clasped tooth from undue strain.

Another object is to provide a ready-made jointed clasp which is simple and inexpensive in construction and which requires 20 little, if any, work on the part of the dentist for fitting the case.

In the accompanying drawings:

Figure 1 is a sectional elevation of a 25 dental plate provided with the improved clasp. Figure 2 is an enlarged perspective view of the clasp. Figure 3 is a longitudinal section thereof. Figure 4 is a plan view of the blank from which the main portion 30 of the clasp is formed. Figure 5 is a similar view of the anchoring spur or tongue.

Similar characters of reference indicate corresponding parts throughout the several views.

The clasp comprises the customary band 35 10 which is adapted to embrace a natural tooth. For molars and bicuspids, the clasp has the usual lug or occlusal rest 11.

Formed integrally with the clasp and 40 located at its rear side is a loop or steeple 12 preferably formed by a tongue 13 extending from the lower edge of the clasp band and bent upwardly and inwardly upon itself, as shown in Figs. 2 and 3. Loosely 45 jointed or hinged to this loop is an anchoring spur 14 which is embedded in the dental plate or saddle 15; or if used in connection with bridge work, is soldered thereto. The attaching end of this anchoring spur in its preferred form, is bent at an 50 angle to its body and is provided with an opening 16 which loosely engages the loop 12. In the normal condition of the clasp, the inwardly-bent end portion 17 of the tongue 13 is preferably spaced from the 55 opposing rear side of the clasp, as shown

in Fig. 3, so as to leave the loop 12 open at its upper end to receive the anchoring spur. After the dentist has applied the spur to the clasp, he may, if he so desires, close the open end of the loop by soldering or otherwise.

The band 10 of the clasp, including the occlusal rest, if used, is formed in a single piece from a flat blank of sheet metal of 60 the shape shown in Fig. 4, or approximately so. This blank comprises a slightly bowed or curved bar 10^a adapted to form the curved band of the clasp; a tongue 11^a projecting from the concave edge of said bar and adapted to form the occlusal rest 11; and a projection 12^a extending in the opposite direction from the convex edge of 65 said bar, and forming the loop-tongue 13. This band and the anchoring spur 14 are 70 stamped from any suitable metal or alloy, preferably an alloy of gold or platinum having the requisite stiffness and elasticity to enable the clasp to retain its form and 75 tightly grip a tooth, while possessing sufficient strength and flexibility to permit the clasp to be repeatedly bent without breaking any of its parts, in refitting or adjusting the same.

This improved construction of the clasp 80 band and the spur-attaching loop renders the device comparatively inexpensive and materially lessens the work required by the dentist in fitting cases.

I claim as my invention:

1. A jointed dental clasp, comprising a band provided with an integral normally-open loop extending vertically thereof and adapted to receive an anchoring spur.

2. A jointed ready-made dental clasp, 90 comprising a band provided with a loop adapted to receive an anchoring spur, said loop consisting of a tongue formed integral with said band and extending upwardly from the lower edge thereof, the upper end 95 of said tongue being bent toward the band.

3. A jointed dental clasp comprising a band having a vertically-extending loop, and an anchoring spur having an opening loosely 100 engaging said loop, the attaching end of 105 said spur being bent at an angle to the body thereof.

4. A dental clasp comprising a band and a tail-piece, said band having integral therewith tail-piece engaging means, said tail-piece having an end thereof at an angle to 110 the plane of said tail-piece, said tail-piece

- having an opening therein through which said tail-piece engaging means is adapted to be inserted and means to prevent the separation of the tail-piece and the band.
5. A dental clasp comprising a band and a tail-piece, said band having tail-pieces engaging means thereon, said means extending outward from said band and then upward substantially parallel with the plane of the band, said tail-piece having an opening therein through which said engaging means is adapted to be inserted to form a connection between said band and said tail-piece whereby vertical, lateral, angular, and rock-
- 15
ing movement between said band and said tail-piece are obtained and means to prevent the separation of the tail-piece and the band.
6. A dental clasp comprising a band and a tail-piece, said band having integral therewith a tail-piece engaging means, said tail-piece having an end thereof at substantially a right angle to the plane of said tail-piece, said tail-piece having an opening therein through which said tail-piece engaging means is adapted to be inserted and means 20 to prevent the separation of the tail-piece and the band.
- 25

REGINALD V. WILLIAMS.
